E. Stockbridge.

UNITED STATES PATENT OFFICE.

ELAM STOCKBRIDGE, OF HOUSTON, TEXAS.

IMPROVEMENT IN COTTON AND HAY PRESSES.

Specification forming part of Letters Patent No. 24,672, dated July 5, 1859.

To all whom it may concern:

Be it known that I, ELAM STOCKBRIDGE, of Houston, in the county of Harris and State of Texas, have invented an Improvement in Horizontal Cotton-Presses for Compressing Cotton, Hay, and other Articles and Substances for Baling; and I do hereby declare that the following is a full, clear, and exact description of the same, reference being had to the annexed drawings, making a part of this specification, in which—

Figure 1 is a longitudinal vertical section of my invention, taken in the line $x x$ of Fig. 2. Fig. 2 is a plan or top view of the same.

Similar letters of reference indicate corresponding parts in the two figures.

My invention is only useful in connection with horizontal toggle-presses, as the gravity of the follower and lever accomplish the same object in vertical presses as that designed to be accomplished in horizontal presses by my invention; and therefore my invention consists in the arrangement, in combination with the ordinary ropes and chains and windlass used in toggle-presses, of auxiliary ropes or chains for drawing a horizontal follower out of a horizontal pressing-box, and the horizontal toggle and main cords or chains into operative position, or bringing the same in position for operation after the first pressing operation has been performed by them.

It is essential to use horizontal toggle-presses, as they avoid the loss of power expended in overcoming the gravity of the follower and the cotton being pressed, and also avoid the labor of carrying the cotton some fifteen feet high to place in the press-box. The expense of building horizontal presses of this character is also much less than that which attends the construction of vertical presses, as the labor of lifting and adjusting the parts to a high position is avoided.

To enable those skilled in the art to fully understand and construct my invention, I will proceed to describe it.

A represents a horizontal frame, in which a press-box, B, is placed. The frame and press-box are both constructed in a strong and durable manner, the box being provided with doors $a b$ at its upper surface, so that the bale may be readily removed therefrom and the loose material placed therein with facility.

C is the follower, which works within the press-box B. This follower has a bar, D, attached to it at right angles, and to the outer end of the bar D two toggles, E E, are attached by bolts or pivots $c c$. The outer end of each toggle E is provided with a friction-roller, d, and these rollers bear against a cross-bar, F, which is firmly secured in the frame A, the ends of said bar projecting some distance each side of the frame A.

From the center of the cross-bar F two bars, $e e$, project at right angles. These bars form the support for a windlass, G, which is simply a shaft or drum having two ropes or chains, $a' b'$, attached to it, so that one will wind upon it as the other is unwound. The rope or chain a' passes through eyes f at the ends of the bar F, and is attached to the ends of the toggles E E, and the rope or chain b' passes through the center of the bar F and around pulleys $g g$, and its ends are also attached to the ends of the toggles E E.

To the windlass G a rope or chain, h , is attached, said rope or chain being connected directly to the bar D, as shown clearly in Fig. 2.

The operation will be readily seen, and is as follows: The follower C is drawn to the outer end of the press-box B and the material to be compressed is placed within said box. The windlass G is then turned in the direction indicated by arrow 1, (see Fig. 2,) and the follower will be forced within the press-box B, in consequence of the rope or chain b' drawing the outer ends of the toggles E E toward each other, and the ends of said toggles bearing against the cross-bar F, the leverage power of course increasing as the follower is forced within the box, and the space correspondingly decreasing. When the compressed article is bound, the bale is removed and the windlass G is turned in the opposite direction, and the follower is drawn out from the box by the rope or chain h , the rope or chain a' drawing outward or extending the toggles E E, so that the rope or chain h may perform its work. The chains or ropes $a' h$ cause the follower to move in a straight line out of the box, the rope h causing a central draft and counteracting the tendency of the follower to bind in its box by the lateral or oblique draft of the ropes or chains $a' a'$, which

steady the levers in their outward movement and assist the central rope in drawing out the follower.

I am aware that the followers of presses have been actuated by means of toggles and ropes or chains, and I therefore do not claim such device broadly and irrespective of the arrangement herein shown and described; but,

Having thus described my invention, what I claim as new, and desire to secure by Letters Patent, is—

The arrangement, in combination with the horizontal ropes or chains $b' b'$, vertical windlass G, horizontal toggles E E, and horizontal follower C, of the auxiliary horizontal ropes or chains $a' a'$ and h , in the manner and for the purposes herein set forth.

ELAM STOCKBRIDGE.
